UNITED STATES PATENT OFFICE

PATRICK J. FITZGERALD, OF TORRINGTON, CONNECTICUT, ASSIGNOR TO THE FITZGERALD MANUFACTURING COMPANY, OF TORRINGTON, CONNECTICUT, A CORPORATION OF CONNECTICUT

ANTIRATTLING DEVICE FOR AUTOMOBILE PANES

Application filed October 5, 1928. Serial No. 310,614.

The present invention relates to improvements in anti-rattling devices such as for automobile panes, and more particularly the sliding door and window panes employed in the closed type of machines.

According to the present invention, a simple and cheaply constructed device is provided which may be readily attached by suitable supporting members to any type of door or window panes, so that its operating elements may engage the sliding pane and hold the same in one position and against rattling.

The invention is characterized by the construction and assemblage of its several parts, as will be more closely described herein-after.

In the drawings:

Figure 1 is a horizontal sectional view through an automobile pane and its casing, showing the present anti-rattling device in elevation.

Fig. 2 is a view of the same device as in Fig. 1, but showing the face of the clamping members and the anti-rattling elements.

Fig. 3 is a view similar to Fig. 1, but of a modified form of the device.

Fig. 4 is a face view of the device shown in Fig. 3.

Fig. 5 is a perspective view of the disassembled sector and operating arm, showing the relative positions of these parts.

The anti-rattling device of the present structure comprises a base by which it may be attached to a door or window casing, a pivot supported by said base, a spring-actuated pivoted sector, and an extending arm carrying an anti-friction roller and adapted to be secured in different angular positions with respect to said spring-actuated sector.

In Fig. 1, the casing 10 has a recess 11 therein with a groove 12 to support a felt 13 which fits around a vertical edge of the pane 14. It has been found in practice that this felt is not sufficient to constantly exert a deadening pressure upon the pane, but the latter soon becomes free to move in the felt, and thus to cause a rattling and

sometimes even breakage of the pane itself.

A base plate 20 has an outwardly turned flange 21 which fits on one side of the casing 10. At the opposite side of the base plate 20 is an upstanding lug 22 to receive the clamping screws 23 which pass through and have their heads supported against the lug 24 on a second clamping member 25. This second clamping member has slots 26 therein (Fig. 2) to receive the guiding rivets 27 which permit and cause this base plate 20 and the clamping plate 25 to move in planes parallel one to another. The intermediate portion of the clamping plate 25 is rebent 55 in a loop 25a, and the clamping plate terminates with an engaging portion or flange 28 which fits beneath a bead on the casing 10. As the screws 23 are drawn tight, the clamping portions or flanges 21, 28 clamp the casing 10 between them and thus secure the base plate 20 firmly in position at the casing edge. The base plate 20 also has the upstanding fingers 30 which are formed 60 integrally by punching from the base plate 20, and have apertures in alignment therethrough to receive the guide or pivot pin 31, which has an enlarged head 32 at one end, and receives a retaining cotter pin 33 65 at the other end, usually with the interposition of a washer 34.

A spring-actuated sector plate 35 has a stop foot 36 to engage the base plate 20 and thus limit its movement of spring-affected 70 rocking in a counterclockwise direction in Fig. 1. This spring-actuated sector 35 also has an extending nose 37 which passes over the loop 38 of a spring 39 which is formed 75 into symmetrical convolutions adjacent its ends. These convolutions are arranged 80 around the pivot pin 31, respectively, between the head 32 and one of the upstanding fingers 30, and between the washer 34 and the other upstanding finger. The extreme 85 ends 40 of the spring rest against the fingers 30. It is apparent that the spring 39 constantly exerts a pressure upon the sector 35 and tends to cause the same to turn in a 90 counterclockwise direction in Fig. 1.

An extending arm 41 is likewise pivoted 100

about the pin 31, and at its end has a rivet 42 serving as a stiff pivotal mounting for a shackle 43 having an axle 44 therein for the anti-friction roller 45, which preferably is formed of fibre or similar relatively soft but resistant material.

The extending arm 41 receives a screw 46 which passes through an arcuate slot 47 in the sector 35, this slot being concentric with the axis of the pivot pin 31.

In locating this form of the device upon an automobile casing for anti-rattling employment in conjunction with the pane therein, the clamping flanges 31, 28 are brought into contact with the edge of the casing 10 in the manner described above. The screw 46 is then loosened, and the pane 14 brought to a position opposite the roller 45, and this roller is brought down against the pane by rocking the extension 41 with respect to the sector 35: the axle 44 is carefully alined to be parallel to the plane of the pane. The roller 45 is pressed forcibly against the pane 14 until the latter is driven into solid contact with the opposite side of the felt 13: the screw 46 may now be tightened; and the device is ready for use. If it is desired to secure a slightly greater spring pressure upon the roller 45, the pane 14 may be dropped, the screw 46 loosened and the arm 41 rocked slightly further in a counterclockwise direction: when the screw 46 is again tightened, the desired pressure will have been obtained.

During the raising and lowering of the pane 14 the relative pressure toward the right in Fig. 1 from this pane upon the roller 45 may cause the sector 35 to be rocked in a clockwise direction slightly, against the action of the spring 39: thus maintaining the anti-friction effect. It will be noted that when the pane 14 is entirely removed from opposite the roller 45, the stop 36 prevents excessive movement of the arm 41.

In the simplified form of the mounting shown in Fig. 3, the base plate 20a is formed simply with a retaining means, which in the present instance comprises the end braces 20b having apertures 20c therein to receive securing screws. The other parts of this construction are the same as before, its operation is the same: and it will be noted that by reason of the simple arrangement, the device is even cheaper in construction, although it may not be so readily placed and removed as the device of Figs. 1 and 2.

I claim:

1. In an anti-rattling device for automobile panes or the like, a base adapted to be attached to the pane casing, a sector and an arm coaxially pivoted on said base, means to secure said sector and said arm together at a selected angular relationship, a roller carried by said arm on an axis at a right

angle to the direction of movement of said pane and adapted to contact the pane, and resilient means to rock said sector and thereby said arm to maintain said roller in contact with said pane.

2. In an anti-rattling device for automobile panes or the like, a base adapted to be attached to the pane casing, upstanding fingers on said base, a sector and an arm coaxially pivoted to said fingers, means to secure said sector and said arm together at a selected angular relationship, a roller carried by said arm and mounted on an axis at a right angle to the direction of movement of said pane and adapted to contact the pane, and resilient means to rock said sector and arm to maintain said roller in contact with said pane.

3. In an anti-rattling device for an automobile pane or the like, a base adapted to be attached to the pane casing, a sector and an arm coaxially pivoted to said base, means to secure said sector and arm together at a selected angular relationship, a shackle mounted on said arm to pivot about a vertical axis, a roller carried by the shackle and mounted on a horizontal axis and adapted to contact the pane, and resilient means to rock said sector and arm to maintain said roller in contact with said pane.

4. In an anti-rattling device for an automobile pane or the like, a base adapted to be attached to the pane casing, a pivot pin supported by said base and having enlarged end members, an arm pivoted on said pin, a roller carried by said arm and adapted to contact the pane, and a spring having a central coil surrounding said pin and reacting at its ends relatively between said base and said arm whereby to maintain said roller in contact with said pane.

5. In an anti-rattling device for an automobile pane or the like, a base adapted to be attached to the pane casing, an arm pivoted on said base, a roller mounted on said arm and adapted to contact the pane and be rotated thereby, resilient means operating relatively between said arm and said base whereby to maintain said roller in contact with said pane, and a stop secured to said arm and adapted to contact said base to limit the movement of said roller when the pane is withdrawn therefrom.

6. In an anti-rattling device for an automobile pane or the like, a base adapted to be attached to the pane casing, a sector and an arm coaxially pivoted on said base, said sector and arm having a slot-and-screw adjustment whereby they may be secured together at a selected angular relationship, a roller carried by said arm and adapted to contact the pane, and resilient means to rock said sector and arm to maintain said roller in contact with said pane.

7. In an anti-rattling device, a base plate

having a projecting flange, a clamping plate
slidable along said base plate and having
a similarly projecting flange, said flanges
being adapted to grip the pane casing,
5 means to hold said plates for relative par-
allel movement, means to draw said flanges
together whereby to clamp said plates upon
the casing, an arm pivotally mounted on said
clamped plates, a roller carried by said arm
10 and adapted to contact the pane, and a
spring to rock said arm to maintain said
roller in contact with said pane.

8. In a device as set forth in claim 7, the
provision of relatively downturned flanges
15 and upturned lugs on said plates, and a
screw engaging said lugs to draw the flanges
together whereby to clamp the plates upon
the casing.

9. In an anti-rattling device for an auto-
20 mobile pane or the like, a base adapted to
be attached to the side of the pane casing,
a sector and an arm coaxially pivoted to
said base and adapted to rock about a ver-
tical axis, means to secure said sector and
25 arm together at a selected angular relation-
ship, a shackle mounted on said arm to
pivot about a vertical axis, a roller carried
by said shackle upon a horizontal axis and
adapted to contact the pane, and resilient
30 means to rock said sector and arm to present
said roller into contact with said pane, said
sector and arm being relatively adjustable
so that the roller may be pressed against
the pane with a desired predetermined
35 pressure.

In testimony whereof, I affix my signa-
ture.

PATRICK J. FITZGERALD.
